SWINGABLE BRACKET FOR CABINETS

Clyde L. Filbert, North Sacramento, Calif.

Application August 16, 1939, Serial No. 290,471

2 Claims. (Cl. 312—184)

This invention relates to a swing bracket for cabinets and has for an object to provide a bracket for holding a can opener or other article in a sanitary condition, and which may be swung into a wall cabinet when not in use, and when in use may be swung into the door opening of the cabinet to permit easy access to the article carried thereby.

A further object is to provide apparatus of this character which will be formed of a few strong simple and durable parts, which will be inexpensive to manufacture, and which will not easily get out of order.

With the above and other objects in view the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawing forming a part of this specification:

Figure 1 is a fragmentary front elevation of a wall cabinet, open, and showing a swing bracket constructed in accordance with the invention, in operative position.

Figure 2 is an end elevation of the wall bracket shown in Figure 1 and showing a conventional can opener carried by the flanges of the bracket.

Figure 3 is a cross sectional view taken on the line 3—3 of Figure 1 showing the swing bracket in top plan.

Figure 4 is a detail perspective view of the swing bracket.

Referring now to the drawing in which like characters of reference designate similar parts in the various views, the swing bracket comprises a hinge bar 10 adapted to be secured to the inner side surface of the casement around the door of a cabinet 11, by screws 9, or other connectors. A plate 12 is carried by the bar for swinging movement into operative or inoperative position. The plate is provided with hinge eyes 13 which coact with hinge eyes 14 carried by the bar to receive a hinge pintle 15. When the plate is in operative position it is located in the door opening and when the plate is in inoperative position it is located within the cabinet.

The plate is provided with flanges 16 providing

dog ears in which a drop bolt 17 is slid, the bolt being interchangeably engageable in either of two sockets 18 formed in the bottom 19 of the cabinet to hold a plate in either of its positions.

The plate is provided with flanges 20 to receive the base of any wall type can opener 21. The plate may be formed of wood, or of metal, and in the event the plate is formed of metal the dog ears 16 and the flanges 20 may be struck up from the metal as shown in Figure 4.

The plate is provided with two sets of dog ears 16 to interchangeably receive the drop bolt to permit the bracket to be used at the right or the left hand side of the cabinet. The plate is also provided with two sets of struck up flanges 20 to receive the can opener 21 when the plate is disposed at either the right or the left hand side of the cabinet.

From the above description it is thought that the invention will be fully understood without further explanation.

What is claimed is:

1. A swingable bracket for cabinets comprising a bar adapted to be secured to the inside surface of the casement around the door opening of a cabinet, a plate hinged to the bar for swinging movement to operative position in said opening or to released position within the cabinet, dog ears on the plate, a drop bolt in said dog ears adapted to engage the cabinet and hold the plate in operative or in released position, and flanges on the plate adapted to receive the base of a can opener.

2. A swingable bracket for cabinets comprising a bar adapted to be secured to the inside surface of the casement around the door opening of a cabinet, a plate hinged to the bar for swinging movement to operative position in said opening or to released position within the cabinet, two sets of dog ears disposed respectively near the upper and lower edges of the plate, a drop bolt interchangeably received in said dog ears for adapting the device to be located at the right or the left hand side of the cabinet, and two sets of flanges disposed respectively near the upper and lower edges of the plate adapted to selectively receive the base of a can opener when the plate is disposed at either the right or the left hand side of the cabinet.
